UNITED STATES PATENT OFFICE.

CARL AUGENSTEIN, OF CRANSTON, AND ROBERT VOGEL, OF PROVIDENCE, RHODE ISLAND, ASSIGNORS TO AUTOMATIC GOLD CHAIN COMPANY, A FIRM COMPOSED OF EDWIN F. M. SPEIDEL AND ALBERT R. SPEIDEL, BOTH OF EDGEWOOD, RHODE ISLAND.

CHAIN.

Application filed December 9, 1926. Serial No. 153,527.

This invention relates to an improved construction of chain or bracelet formed of a plurality of extendible links; and the object of this invention is to construct such a chain or bracelet having an outer guide link formed of sheet stock folded into the desired shape and an inner slide link provided with a hook-shaped portion by which it may be readily connected to and disconnected from the next adjacent link of the bracelet.

A still further object of the invention is to so fold the stock of the guide link so as to provide a rear wall with a longitudinal opening, the edges of the rear wall being provided with inturned, central lips and said lips having abutments against which one end of the operating spring acts for the purpose of pressing the slide link to contracted position.

A still further object of the invention is the provision of a slide link formed into elongated band shape with a hook adjacent one end, one arm of the band being arranged to lie in the slot in the guide link substantially flush with the face thereof to complete its bearing wall, the inturned abutment fingers on the guide link extending between the walls of the band to prevent the hook from being opened except when in extended position.

With these and other objects in view, the invention consists of certain novel features of construction, as will be more fully described, and particularly pointed out in the appended claims.

In the accompanying drawings:

Figure 1 is a perspective view showing a series of links connected together.

Figure 2 is a perspective view showing the under side of the guide link with the slide link removed therefrom and the abutment fingers in extended position before being folded into operative position.

Figure 3 is a view of the underside of this link.

Figure 4 is a cross section on line 4—4 of Figure 3 showing the inturned guide lips on this guide link.

Figure 5 is a perspective view of the slide link showing it as being provided with an

engaging hook at one end.

Figure 6 is a view of the under side of this slide link.

Figure 7 is a central sectional view of this slide link.

Figure 8 is a sectional view showing the slide links in partially extended position in the guide links.

Figure 9 is a sectional edge view showing the links in the same position as shown in Figure 8.

Figure 10 is a section on line 10—10 of Figure 8.

Figure 11 shows the hook of the slide link in position with the tongue depressed to engage the cross bar on the next adjacent guide link.

It is found of advantage in the construction of bracelets of this character, to provide a guide link of sheet stock, the blank of which is folded to provide a broad, front face, narrow edge walls and having inwardly-extending rear wall portions, the edges of which are turned in towards the inner surface of the front wall to provide a longitudinal guiding slot and to provide a band-shaped slide member of elongated hook form with the front arm portion formed of a broad plate to close the space between the links when in extended position, also to provide its rear arm of a narrower width to fit into the longitudinal guide channel in the guide link and set substantially flush with the rear face thereof to complete the bearing wall of this guide link; also to fold the abutment fingers on the inturned lips of the guide link to extend between the front and rear arms of the slide link to prevent the resilient rear arm from being sprung inwardly to open the hook except when in extended position; and the following is a detailed description of the present embodiment of my invention and showing one means by which these advantageous results may be accomplished:

With reference to the drawings, 10 designates the guide link, the blank of which is formed from sheet stock and subsequently folded to provide a broad, front face 11 for ornamentation with relatively narrow side 100

walls 12, the stock extending inwardly from these side walls as at 13 to form portions of the rear wall of this link and the rear edge portions of these walls being provided with an integral cross bar 16 to which the hook of the next adjacent slide link may be readily connected.

We have also provided a slide link 17 which is formed in elongated band-shape, one end being bent into hook form, the front plate 18 of this band being of a width to slide in the space 19 beneath the edges of the inturned lips 14 of the slide link, this plate being of a width to substantially fit between the side walls of this guide link; and one end of this broader plate 18 being turned or bent into hook form as at 20, the opposite flexible arm 21 of this band-shaped slide link being substantially narrower than the broader arm 18 thereof and is of a width to fill the space 22 in the guide link and is preferably set flush with the rear walls 13 thereof for the purpose of completing this wall and providing a full bearing surface of the bracelet links on the arm of the wearer. The forward end 23 of this arm 21 being arranged to extend beneath the edge 24 of the hook 20 to prevent it from opening outwardly.

In assembling the parts this slide link is positioned in the guide link by sliding its broader plate 18 beneath the guide flanges 14 and causing the resilient arm 21 to close the space 22 in the guide link, then a spring 25 is inserted into the slide link with one end abutting against the bridge portion 26 thereof and this spring is then compressed and the fingers 15 are folded inwardly over the end of this spring to provide a forward abutment therefor so as to act upon the slide link to press it towards closed position. After the link units have been so assembled, it is only necessary to extend the slide member of the units successively, insert the hook portion 20 of one through the cross bar 16 in the end of the next adjacent guide link thereby detachably connecting the links into a series of any desired number.

Our improved bracelet or chain is very simple and practical in construction and the unit parts may be readily assembled and the different units detachably connected together by simply hooking one into the other and by which construction a bracelet or chain may be made of any desired length thereby readily adjusting the working length thereof.

The foregoing description is directed solely towards the construction illustrated, but we desire it to be understood that we reserve the privilege of resorting to all the mechanical changes to which the device is susceptible, the invention being defined and limited only by the terms of the appended claims.

We claim:

1. A bracelet structure comprising a series of extendible link units, each having a guide link formed of sheet stock folded to provide a broad front plate with relatively narrow side walls having rear flanges with inturned guiding edge lips forming a space between them, a band-shaped connector link slidable in said guide link formed in elongated hook shape with a closing tongue, one part of said band lying substantially flush with the rear flanges of said guide link completing the rear bearing wall thereof, inturned abutments on said lips and a closing spring, acting between said abutments and the end of said connecting link to be enclosed by said inturned guiding edge lips of the guide link and the rear and front walls of the connecting links.

2. A bracelet structure comprising a series of extendible link units, each having a guide link formed of sheet stock folded to provide a front wall, side walls and portions of a rear wall with their edges spaced apart and turned inwardly forming guiding lips, a band-shaped slide link having a broad plate extending beneath said lips and a narrow plate positioned to complete the rear wall of the guide link between said lips, laterally extending abutment fingers on said lips, a link closing spring acting between said abutment fingers and the fold of said band link and a member on the adjacent end of the next guide link detachably engaged by the hook of the slide link.

3. A bracelet structure comprising a series of extendible link units, each having a guide link formed of sheet stock folded to provide side walls and portions of a rear wall with their edges spaced apart and turned inwardly forming guiding lips, a band-shaped slide link having a broad plate extending beneath said lips and a narrow plate positioned to complete the rear wall of the guide link between said lips, laterally-extending abutment fingers on said lips, a link closing spring acting between said abutment and the fold of said band link, and an integral cross bar on the adjacent end of the guide link detachably engaged by the hook of the slide link, said fingers on the guide link extending beneath the hook tongue to prevent a disengaging action of the hook except when the link parts are in extended position.

4. A bracelet structure comprising a series of extendible link units, each having a guide link formed of sheet stock folded to provide a front wall, side walls and portions of a rear wall with their edges spaced apart and turned inwardly forming guiding lips, a band-shaped slide link having a broad plate extending beneath said lips and a narrow plate or arm positioned when in contracted position to complete the rear wall of the guide link between said lips, fingers on said

5. lips extending inwardly toward each other, a link closing spring positioned between said lips and acting between said abutment fingers and the fold of said band link, and a cross bar on the adjacent end of the next guide link detachably engaged by the hook of the slide link.

10. 5. A bracelet structure comprising a series of extendible link units, each having a guide link formed of sheet stock folded to provide a broad front plate with relatively narrow side walls having rear flanges with inturned guiding edge lips forming a space between

them, a band-shaped connector link slidable in said guide link formed in elongated hook 15 shape with a closing tongue, inturned abutments on said lips, and a closing spring, acting between said abutments and the end of said connecting link to be enclosed by said inturned guiding edge lips of the guide link 20 and the rear and front walls of the connecting links.

In testimony whereof we affix our signatures.

CARL AUGENSTEIN.
ROBERT VOGEL.
